[57] CLAIM

The ornamental design for a handrail for vehicles, as shown.

DESCRIPTION

FIG. 1 is an isometric view of a handrail for vehicles showing my new design;

FIG. 2 is a side elevational view thereof to an enlarged scale;

FIG. 3 is a front elevational view thereof to an enlarged scale;

FIG. 4 is a rear elevational view thereof to an enlarged scale;

FIG. 5 is a bottom plan view thereof to an enlarged scale; and

FIG. 6 is a top plan view thereof to an enlarged scale.
